UNITED STATES PATENT OFFICE.

ALBERT DE PUYDT AND HIPPOLYTE DE VILMINK, OF LIEGE, BELGIUM.

HYDRAULIC TRANSMISSION OF POWER.

1,333,012.

Specification of Letters Patent.

Patented Mar. 9, 1920.

Application filed July 18, 1918. Serial No. 311,865.

To all whom it may concern:

Be it known that we, ALBERT DE PUYDT and HIPPOLYTE DE VILMINK, subjects of the King of Belgium, and residents of Liege, Belgium, have invented certain new and useful Improvements in Hydraulic Transmission of Power; and we do hereby declare the following to be a full, clear, and exact description of the invention, such as will enable others skilled in the art to which it applies to make and use the same, reference being had to the accompanying drawings, and to letters or figures of reference marked therein, which form a part of this specification.

This invention relates to a system of power transmission in which a motor, which may be a constant speed motor, operates a pump supplying liquid under pressure to a liquid motor, designed to operate at variable speed.

In mechanisms of this kind known hitherto piston pumps have been employed. These are inconvenient inasmuch as they complicate the system very much because it is necessary to provide means for reducing the output of the piston pump in proportion to the consumption of the liquid motor, which varies with its speed.

This inconvenience is avoided in the subject of the present invention by replacing the piston pumps by centrifugal pumps in which the output is self-limiting.

Moreover, the use of centrifugal pumps enables the speed of the liquid motor to be controlled by varying the area of the discharge opening of the motor; this is a very simple method of regulation which prevents sudden changes of motion or hammering of the liquid in the motor, and, further, it enables a braking effect to be secured when the motor is maintained in movement by the momentum of the parts which it drives. The direction of movement of the liquid motor may be reversed by reversing, for instance by means of a four-way cock, the functions of the admission and discharge pipes.

The invention further contemplates a means of reducing the expenditure of energy when the liquid motor is operating at a low output. This means consists in lessening the pressure of the liquid supplied to the motor. For this purpose several centrifugal pumps, arranged in series, are employed to produce the normal working pressure, and of these one or more can be put out of action,

or stopped, when only a reduced pressure is required.

The drawings show by way of example one form of construction of the invention applied to a tractor.

Figure 1 is a side view of the installation with parts in section.

Fig. 2 is an end view of the constant speed motor and the centrifugal pumps 2.

Fig. 3 is an enlarged detail section of the centrifugal pumps.

In the form of construction shown, a three-phase motor 1, which may be of constant speed, is directly coupled to the shaft 70 of three centrifugal pumps placed within the same casing. The three rotary members of the pumps operate in series if the cocks 6' and 7' are closed and cock 8' is opened. The pressure is reduced to two thirds if the cock 75 7' alone is opened; and a pressure of one third can be obtained by opening the cock 6' only.

The variable speed motor 9 is a motor with a piston, which drives, through a connecting rod and crank, the axle 10 of the tractor. The valve cylinder 11, in which two distributing pistons 12 reciprocate under the action of the lever 13, is connected on the one hand with the pipe 14 by a central port 15, and on the other hand with the pipe 17 by two ports 16, one at each end of the cylinder. The two pipes 14 and 17 serve alternatively as admission and discharge pipes for the motor 9, and for this purpose are connected to a four-way cock 18, which controls also the pipe 8, by which liquid is supplied from the pumps, and the pipe 19 by which liquid is returned to the reservoir 5. According to the position of the cock 18 95 liquid supplied through the pipe 8 may be forwarded through the pipe 14, serving as an admission pipe and returned to the reservoir through pipes 17 and 19. The motor will drive in one direction or the other according to the position of the cock 18.

Each of the pipes 14 and 17 is also provided with a cock 20, 21, intended for use when the pipe is acting as a discharge pipe; 105 by more or less throttling the discharge pipe by means of this cock, and so producing a back-pressure, the speed of the motor 9 may be lessened and a braking effect exerted upon the vehicle.

The cocks 20 and 21 may be omitted if the cock 18 is so arranged that the discharge

through it can be closed before its other openings. This end may, for instance, be attained by providing at 18 a slide valve instead of an ordinary four-way cock.

5 The pipe 8 has a branch connecting with a reservoir 22 containing air, the purpose of which is to take up shocks in the mass of the liquid. This reservoir is provided with a manometer 23.

10 The use of several pumps in series enables the pressure of the liquid supplied to the hydraulic motor to be lessened when the motor is operating on small output, for instance, when the tractor is traveling light.

15 It is obvious that the constant-speed motor 1 may be any sort of electric motor, internal combustion engine, and so forth, and may drive the pumps through any suitable mechanism whatever. The motor may 20 drive one or more groups of pumps. Similarly, each group of pumps may control several variable speed motors.

In this case, without increasing the output of liquid, the speed of some of the motors may be increased by putting one or 25 more others out of action.

The motor shown may be put out of action by means of the three-way cock 24. If the shaft 10 is rotated by another motor, the 30 motor put out of action will operate, owing to the pipe 25, as a pump short-circuited on itself. The pressure within this short-circuited system will be the pressure due to the pump 2 or atmospheric pressure according to the position of the cock 18, *i. e.* according to the direction of rotation of the motor.

The liquid employed may be water, oil, glycerin or any suitable liquid.

40 What we claim is:

1. In a tractor, the combination, with the driving wheels and their axle, of a hydraulic motor comprising a cylinder and a piston reciprocating therein and connected 45 with said axle; a centrifugal pump; a pipe system connecting said pump and hydraulic motor for supplying motive fluid under pressure from the former to the latter; and an electric motor for operating said pump 50 at a constant speed.

2. In a tractor, the combination, with the driving wheels and their axle, of a hydraulic motor comprising a cylinder and a piston reciprocating therein and connected with said axle; a centrifugal pump; a pipe system connecting said pump and hydraulic motor for supplying motive fluid under pressure from the former to the latter; means for regulating the discharge from the hydraulic motor to vary its speed; and an 60 electric motor for operating said pump at a constant speed.

3. In a tractor, the combination, with the driving wheels and their axle, of a hydraulic motor comprising a cylinder and a piston reciprocating therein and connected with said axle; a centrifugal pump; a pipe system connecting said pump and hydraulic motor for supplying motive fluid under pressure from the former to the latter; 70 means for reversing the flow of the motive fluid through said pipe system to reverse the direction of movement of the hydraulic motor; and an electric motor for operating said pump at a constant speed.

4. In a tractor, the combination, with the driving wheels and their axle, of a hydraulic motor comprising a cylinder and a piston reciprocating therein and connected with said axle; a centrifugal pump; a fluid reservoir in pipe communication with the pump; a pipe system comprising a set of four pipes having a common point of intersection, said set including a supply pipe leading from said pump, a return pipe leading to said reservoir, and a pair of pipes connected to said hydraulic motor and constituting inlet and exhaust means for the motive fluids; a four-way valve at the point of intersection of said pipes for controlling 90 the direction of flow therethrough; and an electric motor for operating said pump at a constant speed.

In testimony whereof we affix our signatures in presence of two witnesses.

ALBERT DE PUYDT.

HIPPOLYTE DE VLEMINCK.
